UNITED STATES PATENT OFFICE.

GEORGE W. SMILLIE, OF NEWARK, NEW JERSEY.

CAR-COUPING.

SPECIFICATION forming part of Letters Patent No. 655,357, dated August 7, 1900.

Application filed December 19, 1899. Serial No. 740,870. (No model.)

To all whom it may concern:

Be it known that I, GEORGE W. SMILLIE, a citizen of the United States, and a resident of Newark, Essex county, State of New Jersey, 5 have invented certain new and useful Improvements in Car-Couplers, of which the following is a specification, reference being had to the accompanying drawings, forming part thereof.

10 This invention relates to car-couplers, and more particularly to that class of car-couplers known as the "vertical plane" type. In this class of couplers, as well understood, provision is made to permit a certain limited play 15 between two connecting couplers, so as to allow a lateral turning movement of the same relative to each other when the cars are passing upon a curve. Such lateral movement, however, is necessarily limited in order to 20 prevent disengagement of the couplers from each other and is not sufficient to allow the cars to pass upon a very sharp curve without causing undue lateral strain upon the couplers in their bearings. Therefore it has been 25 the object of my invention to provide an improved coupler that will readily yield or adapt itself to any lateral strain thereon when the cars are passing upon a curve and when such strain is removed automatically assume its 30 normal central position.

To this end my invention consists in the construction and combination of parts, as hereinafter set forth in detail, and pointed out in the claims.

35 Referring to the drawings, Figure 1 is a plan view of a coupler embodying my invention, and Fig. 2 is a side elevation of the same.

To explain in detail, 1 represents the draw-head of the coupler, the same being provided 40 with the usual pivoted horizontally-swinging hook or knuckle 2 and the vertically-movable locking-pin 3 for engaging with the inner arm of said knuckle to hold the same in its normal closed position.

45 The draw-head 1 is pivotally connected with its supporting draw-bar 4, so as to be capable of having a laterally-swinging movement relative thereto, as indicated by dotted lines in Fig. 1, the same, as herein shown, being provided with two arms or extensions 5 5 on its 50 rear side, which extend into the opening in the front end of the hollow draw-bar, a pivot-

pin 6 being passed vertically through the draw-bar and through openings in said arms or extensions 5 5 to pivotally unite the draw- 55 head 1 with said draw-bar 4.

It is of course obvious that the draw-head should be movably held in a normal central position relative to the draw-bar in order to be in proper position to receive another coup- 60 ler in engagement therewith when two cars are brought together. To insure such normal position of the draw-head, I have supported two longitudinally-movable spring-pressed rods 7 7 in suitable bearings on the 65 opposite sides of the draw-bar, with one end of the same engaging with the rear side of the draw-head at opposite sides of its pivotal connection with the draw-bar, as shown.

The draw-bar is provided with two laterally-projecting flanges 8 8 at its front end and on opposite sides thereof, having openings through which the front ends of the rods 7 7 extend to be supported and guided. The rear ends of the said rods 7 7, as shown, are sup- 70 ported between two lugs 9 9 on each side of the draw-bar, a pin 10 passing through open- 75 ings in said lugs adjacent to their ends to retain the rods in position between the same. Coiled springs 11 11 are located on said rods 80 with one end having a bearing against the said lugs 9 9 and their opposite or forward ends bearing against a fixed collar 12, located on the said rods. When the draw-head is in 85 its normal central position relative to the draw-bar, with the adjacent ends of the rods 7 7 in contact with its rear side, the collars 12 on the said rods are in contact with the rear wall of the supporting and guiding flanges 8 8. As the draw-head is swung laterally 90 relative to the draw-bar, however, as indicated by dotted lines in Fig. 1, the rod 7, against which the draw-head swings, is forced backward against the pressure of the spring 11, the latter being thereby compressed un- 95 der the action of the collar 12 on said rod.

Thereafter when the cars again move upon a straight portion of the road or in the event of the couplers being disconnected the action of the compressed spring 11 upon the rod 7 100 forces the latter forward and causes the draw-head to again assume its normal central po- sition.

An important feature of my present inven-

tion is: The spring-pressed rods 77 being supported on the draw-bar wholly independent of connection with the draw-head enables the latter to be disconnected from the draw-bar 5 at any time for the purpose of repairs or otherwise without in any way interfering with the said rods or their controlling-springs.

Having thus set forth my invention, what I claim, and desire to secure by Letters Patent, is—

1. In a car-coupler, the combination, of the draw-bar, the draw-head pivotally connected with said draw-bar, and two longitudinally-movable spring-pressed rods supported by 15 said draw-bar with one end of the same acting against the draw-head and yieldingly holding the latter in a normal central position relative to the draw-bar, the said spring-

pressed rods being supported by the latter independent of connection with the draw-head. 20

2. In a car-coupler, the combination, of the draw-bar having two laterally-projecting flanges on opposite sides thereof, the draw-head pivotally connected with said draw-bar, and two longitudinally-movable spring-pressed rods supported by the draw-bar with one end of the same extending through openings in said laterally-projecting flanges and acting against the draw-head to yieldingly hold the latter in a normal central position 25 relative to the draw-bar, for the purpose set forth.

GEO. W. SMILLIE.
